Primary Examiner — Catherine Ho*Assistant Examiner* — Tyenne A. Fulton-Crosson(74) *Attorney, Agent, or Firm* — Daniel M. Cohn;
Howard M. Cohn(57) **CLAIM**

The ornamental design for a drawer as shown and described.

DESCRIPTION

FIG. 1 is a perspective view of a drawer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the drawer where the drawer is in a configuration of use.

The broken lines in the drawings depict portions of the drawer that form no part of the claimed design.

1 Claim, 9 Drawing Sheets(56)
